UNITED STATES PATENT OFFICE.

GEORGE A. BURNHAM, OF SAUGUS, MASSACHUSETTS, ASSIGNOR TO SEARS B. CONDIT,
OF BROOKLINE, MASSACHUSETTS.

HIGH-POTENTIAL ELECTRIC SWITCH.

Application filed March 12, 1921. Serial No. 451,921.

To all whom it may concern:

Be it known that I, GEORGE A. BURNHAM, a citizen of the United States, residing at Saugus, in the county of Essex and State of Massachusetts, have invented an Improvement in High-Potential Electric Switches, of which the following is a specification.

This invention relates to electric switches and has particular reference to oil immersed switches adapted to control circuits of relatively high potential.

For the control of circuits of say, 50,000 volts and above, it has been common practice to provide a separate switch for each phase of a multi-phase circuit and, because of the relatively great distance provided between the conducting and other components of the switch, made necessary to provide sufficient insulation of the conducting components, each switch unit has relatively great bulk and is correspondingly expensive. The installation expense of the switches, also, is considerable as the switch units are usually mounted on concrete foundations. Also by reason of their bulk, difficulties are experienced in shipping them from the factory to the installation location and transportation expenses are considerable. The switches are vented and, while they are more or less weather proof, yet, due to expansion and contraction of the air and other gases in the expansion space in the switch, due to variations of atmospheric temperature, an appreciable amount of moisture collects in the switch and mixes with the oil and impairs its insulating property. With high potentials a relatively small amount of water in the oil will break down the oil insulation of the conducting components of the switch. Furthermore, the viscosity of the oil in the switch is affected by temperature changes and, in winter the oil thickens or becomes more viscous with the result that the speed of the movable switch members to open position, and, consequently, the current interrupting capacity of the switch, is reduced.

An object of this invention is to provide an oil switch adapted to control circuits of relatively high potential, of relatively simple and inexpensive construction, wherein all the switch members for a multi-phase circuit may be contained in a common casing; that is so arranged that the oil will be kept at substantially constant temperature at all times; which may have a relatively high

head of oil above the contact member whereby to improve the interrupting capacity; and which will occupy but relatively little space when in transportation.

A further object of the invention is generally to improve the construction and operation of an electric switch.

The switch embodying the invention is mainly fabricated at the place of installation. Instead of providing large oil receptacles of sheet steel to contain the switch members, I sink a pit into the ground and line the pit with, preferably, reinforced concrete to form the oil container; and the lined pit is made of sufficient size to contain all switch members of a multi-phase circuit. The expense of preparing the concrete-lined pit may not greatly exceed the cost of making the concrete foundation necessary to support the usual super-surface type of switches. The depth of the pit is preferably such that the major portion of the body of oil will be below frost level whereby the temperature of the oil will remain practically constant throughout all the seasons of the year and, in any event, the temperature changes will be reduced. The conducting components are carried by an inexpensive frame construction and supported from the side walls of the pit and submerged beneath the oil; and some saving in insulator costs, due to the submergence of insulators, will be effected.

The expansion chamber of the switch is relatively great and the current-interrupting capacity is correspondingly increased. Current and potential transformers may also be immersed in the oil, and also the switch operating mechanism.

Fig. 1 is a vertical section of a sub-surface electric switch embodying the invention.

Fig. 2 is a transverse section of the switch of Fig. 1.

Fig. 3 is a plan detail of the cover of the switch.

Fig. 4 is a vertical section through one of the stationary switch members.

In carrying out the invention a well or pit 10, preferably cylindrical, although it may be of other suitable shape, is sunk below the surface A of the ground to a suitable depth. The pit is lined with concrete or other suitable material to form an oil container 12 and the inner face of the container is made smooth and may be given a superficial oil-impermeable coating. Reinforcing members 110

13 may be incorporated in the wall of the container to reinforce and strengthen it. The stationary switch members 14 and movable switch members 15 and operating mechanism 16 may be supported on the frame 17 which latter may be secured, preferably removably, to stationary supporting members 18 inset in the wall of the container and extended into the oil space. The oil in the container is adapted to extend above the top of the stationary switch members so that said members will be completely submerged. With this arrangement it is practicable to use oil-filled insulators for the stationary switch members which type of insulator previously has been found to be impracticable in many instances because of the difficulty of maintaining it full of oil.

Fig. 4 illustrates such an oil filled insulator wherein the conducting rod 19 of the stationary switch member is enclosed within and spaced from the wall of the tubular insulator 20 by the space 21 which is adapted to be filled with oil. The insulator, with this arrangement, serves principally to support the switch member mechanically and consequently can be cheaply constructed. Current transformers 22 may be disposed about certain of the insulators 20 and supported either by said insulators or by the frame 17 and may also be completely immersed in the oil.

The level of the oil in the container is adapted preferably to be at such a distance below the surface of the ground that the main portion of the body of oil may be below frost level whereby the switch will be subjected to the least temperature variation although, in any event, the temperature variations will be reduced over atmospheric temperature variations.

The wall of the oil container may extend suitably above the surface of the ground; as at 12, and the container may be closed by the cover 23 which may be removable or not, as desired. Insulators 24 are supported by the cover through which the switch leads 25 are passed to connect the stationary switch members with the line 26 which may be supported by the towers 27. The cover 23 may be provided with a manhole 28 by which access to the interior of the switch may be obtained and the manhole may also serve as a vent for the switch.

The circuit leads for the electrically-controlled switch-operating mechanism may be contained in the conduit 29 which extends through the cover into the switch.

By reason of the construction above set forth a relatively great expansion chamber B is provided above the oil in the switch whereby the interrupting capacity of the switch may be comparatively great.

The frame 17 with its connected components may be drawn out of the switch for in-

spection and repair, when desired, and the oil in the switch may be drawn out by suitable means, as pumps, not shown.

It will be noted that, with the construction above set forth, elaborate oil receptacles, insulators and the like are obviated. Transportation expenses are reduced as the insulators, switch-members, operating mechanism, and switch frame, which constitute practically all the switch components not fabricated at the installation location, have but relatively little bulk.

It will also be noted, that, by installing the switch beneath the surface of the ground, temperature changes of the oil due to atmospheric temperature variations are relatively small, as the concrete or cement lining comprising the oil receptacle, and the ground are, relatively speaking, heat insulators, and the ground by reason of its poor heat conducting qualities and great mass has its temperature but slowly changed in response to atmospheric changes of temperature. It, furthermore, will act to absorb an elevated temperature of the oil due to heating of the switch, and thereby keep the switch cool.

It is obvious that the invention may be embodied in other modifications without departing from the spirit thereof.

I claim:

1. An oil immersed electric switch having an oil receptacle comprising a pit sunk in the ground and having a lining of an oil-impervious material, and stationary and movable switch-members and an insulating liquid contained in said pit.

2. An oil immersed electric switch having an oil receptacle comprising a pit sunk in the ground and a cement lining in the pit and stationary and movable switch-members and a body of oil contained in said pit.

3. An oil immersed electric switch having an oil receptacle formed of cement and contained in a pit sunk in the ground, and movable and stationary switch members contained in the oil in said receptacle.

4. An oil immersed electric switch having an oil receptacle comprising a pit sunk in the ground and a wall of oil-impervious material lining the sides and bottom of the pit, said wall extended above the surface of the ground, a cover received on top of said wall, and switch members and oil received in said receptacle.

5. An oil immersed electric switch having a receptacle arranged to contain a body of oil below the surface of the ground, a cover carried by said receptacle above the surface of the ground, and switch members immersed in the oil in said receptacle.

6. An electric switch having an oil receptacle comprising a well sunk below the surface of the ground adapted to contain oil, and switch members immersed in the oil in the well.

7. An electric switch having an oil receptacle comprising a well sunk below the surface of the ground adapted to contain oil, stationary and movable switch members immersed in the oil in the well, a cover over the well at the surface of the ground and insulators carried by said cover adapted to insulate circuit leads extended to said stationary switch members. 5
- 10 8. An oil immersed electric switch having a receptacle adapted to contain oil and an expansion space above the oil, a cover for the receptacle, movable and stationary switch members disposed beneath said cover and submerged in the oil in said receptacle, insulators carried by said cover, and leads extended through said insulators and connected with said stationary switch members. 15
- 15 9. An oil immersed electric switch having a receptacle adapted to contain oil and an expansion space above the oil, a cover for the receptacle, a frame carried by said receptacle and stationary and movable switch members and operating mechanism all supported by said frame and submerged in the oil in said receptacle, insulators carried by said cover, and leads extended through said insulators to said switch-members. 20
- 20 10. An oil immersed electric switch com- 30
- prising a receptacle adapted to contain oil, stationary and movable switch members and switch operating mechanism, all submerged in the oil in said receptacle, said stationary switch members comprising insulators having contact members at the bottom ends thereof and conductors extended through said insulators and connected with said contact members, and circuit leads entering the oil in said receptacle and connected with the upper ends of the conductors in said submerged switch members. 35
11. An oil immersed electric switch having an oil receptacle formed with cement walls, supports projecting inwardly from said walls, a frame supported by said supports and stationary and movable switch members and operating mechanism carried by said frame. 40
12. An oil immersed electric switch having an oil receptacle formed with cement walls, supports embedded in said walls and projecting into the oil space, a frame supported by said supports and stationary and movable switch members carried by said frame. 45
- 50
- 55
- In testimony whereof, I have signed my name to this specification.

GEORGE A. BURNHAM.
